STAPLING MACHINE

Max Vogel, Bridgeport, Conn., assignor to Neva-Clog Products, Inc., Bridgeport, Conn., a corporation of Connecticut

Application October 4, 1938, Serial No. 233,180

15 Claims. (Cl. 1-3)

The present invention relates to an improvement in stapling machines, and has for an object to provide a staple machine of simple and inexpensive construction which will enable the staple strip to be loaded upon the staple rail with greater facility than has been possible in stapling machines heretofore in use. In these previous machines various methods have been employed for loading the staple strip, principal of which have been the methods of loading from the rear by first removing the staple strip pusher, and loading from the front by first removing or displacing a closure or gate at the front to expose the staple strip passage. Another previous method consisted in loading from the top of the staple rail by first removing or raising the housing to expose the top of the staple rail, the staple rail in this case being provided with fixed side walls outwardly spaced from the sides of the staple rail. This construction enables the strip to be dropped into place by first inserting the side leg portions of the strip into the narrow channels between the sides of the rail and the fixed side walls. It is particularly proposed in the present invention to provide a staple rail structure, normally enclosed by a housing member, which housing member upon being opened exposes the rail entirely at its top, front and sides, so that the strip may be readily placed thereon or removed with the fingers conveniently gripping the strip at the sides.

It is further proposed to provide a housing having means which in the closed position forms a retainer or upper limit means for the upper side of the staple strip, and also having front wall means which in the closed position provides a forward abutment for the staple strip, and which also cooperates with the forward end of the staple rail to provide a staple driving passage. Another object is to provide such front wall which with side walls bent rearwardly therefrom provide a guide for the staple driving plunger, and to this end it is proposed to provide milled channels upon the inner surface of the metal forming the housing, which milled channels provide bending lines for the side walls and channel guides for the side edges of the plunger.

A further object is to provide a structure in which the housing is enclosed at its upper side by means of a hinged closure member which also provides the compressible head for actuating the plunger. It is further proposed to provide spring means normally retaining said closure in its raised position, such spring means also consti-

tuting a driving connection between the closure member and the staple driving plunger.

It is further proposed to provide a resilient facing member formed of soft material, such as sponge rubber, and which is removably attached to the closure member by resilient buttons or the like formed upon the facing member and interlockingly inserted in holes in the closure member, to the end that the closure member is provided with a soft surface for comfortable engagement by the hand as it compresses the closure member to drive the staple. Furthermore the stapling machine is given an attractive appearance through the fact that the facing may be of a contrasting color and may be conveniently moulded into streamlined shapes, and may also be readily removed and replaced when it becomes worn or soiled.

Another object is to provide pusher means for the staple strip which pusher means is normally drawn forwardly under spring action, and which cooperates with the housing so that upon opening the housing for the purpose of loading the machine with a staple strip the pusher will be locked against forward movement, thus preventing any possibility of staples remaining upon the rail being shot forwardly therefrom.

It is proposed, in one embodiment of the invention to provide pusher means which in the normal operating position is interlocked with the housing to retain the latter closed, such pusher means adapted upon being retracted to its locked position to release the housing to allow it to be raised. In this embodiment it is also proposed to provide spring means for automatically raising the housing when the housing is released by the pusher means, and further to provide means whereby the pusher means is automatically released when the housing is closed.

In another embodiment it is proposed to provide pusher means which will be automatically locked in any position where it happens to be when the housing is raised. It is further proposed to provide spring means for yieldably retaining the housing in either closed or opened position.

Another object is to provide a stapling machine in which during driving of a staple, the forward pressure of the pusher on the staple strip will be withheld. To this end it is proposed to provide cooperative means acting between the pusher rail, and housing whereby when the staple driving mechanism is actuated the pusher is retained against exerting forward pressure on the staple strip.

A further object of the invention is to provide a stapling machine, which in addition to its normal use in relation to an anvil base clinching the staple legs, may be swung into an open position for use as a tacker, and it is further proposed to provide means for yieldably retaining the machine in such open tacker position, whereby it may be more conveniently handled, utilizing the anvil base member as a handle.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a side elevation of a stapling machine according to one exemplary embodiment of the invention.

Fig. 2 is a top plan view, partially broken away.

Fig. 3 is a rear end elevation.

Fig. 4 is a front end elevation.

Fig. 5 is a transverse vertical sectional view, taken along the line 5—5 of Fig. 1.

Fig. 6 is a longitudinal vertical sectional view, showing the housing raised to expose the staple rail for the loading of a staple strip thereon.

Fig. 7 is a horizontal sectional bottom plan view, taken along the line 7—7 of Fig. 6.

Fig. 8 is a side elevation, partially broken away, showing the anvil base member swung into its position to permit use of the stapling machine as a tacker.

Fig. 9 is a longitudinal vertical sectional view of a modified form of the invention, the dot-and-dash lines showing the anvil base member swung to its position to permit use of the stapling machine as a tacker.

Fig. 10 is a horizontal sectional bottom view, taken along the line 10—10 of Fig. 9.

Fig. 11 is a rear end elevation.

Fig. 12 is a vertical sectional view taken along the line 12—12 of Fig. 9.

Fig. 13 is a vertical sectional view taken along the line 13—13 of Fig. 9.

Fig. 14 is a side elevation, partially broken away, showing the housing member raised to expose the staple rail.

Fig. 15 is a horizontal sectional top plan view, taken along the line 15—15 of Fig. 14.

Fig. 16 is a fragmentary side elevation of a modified form of rail and staple strip pusher showing the normal operative position of the pusher with the housing member closed.

Fig. 17 is a similar view showing the housing member open and the pusher member in its automatically moved locked position.

Similar reference characters indicate corresponding parts throughout the several figures of the drawings.

Referring particularly to Figs. 1 to 8 of the drawings, the stapling machine according to the exemplary illustrated embodiment of the invention shown therein comprises a sheet metal base member 10 having outwardly beveled side walls, provided near its forward edge with an upwardly embossed anvil portion 11, having an anvil recess 12 pressed therein, for the purpose of clinching the staple legs as the staples are driven in the usual manner. Near the rearward edge there is secured the bracket for pivotally mounting the staple rail, housing, closure head, and associated parts, this bracket being of U-shape and consisting of the vertically disposed parallel sides

13—13 and a transverse connecting portion 14, the sides being inserted upwardly through slots 15—15 provided in the base 10 and the portion 14 engaging the under surface of the base 10 where it is secured by spot-welding, or it may be riveted, or otherwise suitably secured.

The staple rail 16 is in the form of an inverted U-cross-sectional channel member, the rearward end portions of the side walls being extended to form mounting ears 17—17 provided with aligned apertures 18—18 to receive the pivot pin 19 supported between the sides 13—13 of the mounting bracket. The outer surfaces of the ears 17 are slightly inwardly offset with respect to the outer surfaces of the main portion of the rail, by means of shoulders 20, for the purpose of providing a clearance space between these ears and the sides 13 of the bracket for the pivotally mounted ends of the housing member and dome-head member, as will presently more fully appear. The upper surface of the rail adjacent the shoulders 20 is inclined downwardly and rearwardly, as at 21 to provide a camming surface for positioning the staple strip pusher in its locking relation, as will presently more fully appear, and the lower edges of the side walls of the rail are provided adjacent the shoulders 20 with inclined portions 22 extending downwardly and rearwardly from an abutment wall 23 with which the staple strip pusher is adapted to interlock in its retracted position, as will also presently more fully appear.

The staple strip pusher 24 is of inverted U-shape cross-section, and is adapted to slidably engage upon the staple rail in parallel relation forwardly of the inclined edge portions 22, being provided at the lower edges of its side walls with inwardly and upwardly bent clip lugs 25 which extend beneath and within the side walls of the rail. Two of these lugs are provided at each side, these being in spaced relation and there being finger grip portions 26—26 between them at each side, and which are adapted to cooperate with the housing member to retain it in closed position, as will hereinafter more fully appear, being provided for this purpose with locking flanges 26a bent upwardly, inwardly and downwardly. The forward lugs 25 are spaced rearwardly from the forward edge of the pusher so that the forwardly projected position of the pusher is limited by abutment with a lug 27 bent inwardly from one side wall of the rail, the forward edge of the pusher being at the same time in alignment with the forward edge of the rail. The pusher is drawn forwardly by means of an elongated coil spring 28 which extends about a post 29 secured to the under side of the staple rail near its forward end, one end of this spring being connected to a lug 30 extended from one of the clip lugs 25 and the other end being connected to a post 31 secured to one of the side walls of the rail near its rearward end.

A leaf spring 32 is secured by a rivet 33 to the upper surface of the rail rearwardly of the shoulders 20 and projects forwardly over the inclined cam surface 21 of the rail, its end being deflected upwardly for the purpose of guiding the pusher beneath it when the pusher is retracted. In the normal operative position of the pusher it is drawn forwardly by the spring in parallel relation to the rail to push the staple strip forwardly, and in this relation it also locks the housing member in closed position, as will presently more fully appear. When manually drawn to retracted position, for the purpose of

reloading, the rearward edge of the pusher enters beneath the spring 32 and as the forward clip lugs 25 move rearwardly of the abutment walls 23 the spring tilts the pusher against the camming surface 21 bringing the forward edges of the forward clip lugs 25 into locking relation with the abutment wall 23, as shown in Fig. 6, the spring 28 drawing the pusher forwardly and thus retaining it in this retracted position, and from which it is adapted to be released automatically upon closing of the housing member, after the staple strip is placed upon the rail as will be more fully pointed out.

The housing member comprises a vertically disposed front wall 34 and side walls 35-35 bent rearwardly therefrom in parallel spaced relation to each other, provided at their rearward ends with apertured bearing portions 36-36, pivotally mounted upon the pivot pin 19 between the side walls 15-15 of the bracket member. At the inner surface of the housing at the point where the side walls are bent rearwardly from the front wall there are provided vertically disposed milled slots 37-37, which constitute bending lines for the side walls and also channel guideways for the vertical edges of the staple driving plunger 38.

In each of the side walls 35 there is provided a longitudinally extending outwardly embossed channel rib 39 providing longitudinal concave recesses upon the inner surfaces of the side walls, and within which the curled edges 40-40 of the transversely disposed longitudinally extending staple strip retaining member 41 are secured by welding. The ribs 39 and the retaining member 41 give to the housing member an extremely rigid structure, enabling it to be constructed of relatively thin metal without sacrifice of strength.

In the closed position of the housing member, as shown in Figs. 1 to 5, the side walls 35 are outwardly spaced from the side walls of the rail, the retaining member 41 is upwardly spaced from the upper surface of the rail and the front wall 34 is forwardly spaced from the forward end of the rail, thus providing a channel for the staple strip and pusher and a staple driving passage through which the individual staples are driven upon actuation of the staple driving plunger. At the lower edges of the side walls 35-35, which edges are parallel to the rail in the closed position, there are provided outwardly bent flanges 42-42, the rearward ends of which terminate just slightly rearwardly of the abutment wall 23 and which flanges are adapted to be interlockingly engaged by the finger grip portions of the pusher in the closed operative position as shown in Fig. 1, with the inwardly and downwardly bent flanges 26a of the finger grip portions 26 locking the housing member against opening movement within a predetermined range of movement of the pusher member determined by the length of the flanges 42-42. Upon retraction of the pusher beyond said predetermined range as shown in Fig. 6 the finger grip portions are disengaged from the flanges 42, thus releasing the housing member, so that it may be raised.

The closure head member is disposed in the upper open side of the housing member and comprises a top wall 43, a front wall 44, and side walls 45-45, the rearward ends of the side walls being provided with apertured mounting portions 46 pivotally mounted upon the pin 19 between the outer surfaces of the bearing portions 17-17 of the rail and the bearing portions 36-36 of the housing member.

A cross-pin 47 extends between and is secured to the side walls 35-35 of the housing member and has the curled portion 48 of the hair-pin spring 49 engaged thereon, the forwardly extending legs of this spring, which are connected at their forward ends by the bend between the legs, extending through a slot 50 in the front wall 44 of the closure head member, and through a slot 52 in the front wall 34 of the housing member, this slot 52 adapted to limit the raised and depressed positions of the plunger and closure head by engagement of the spring with the respective upper and lower ends of the slot. The rearwardly extending legs of the spring 49 engage the under-surface of the top wall 43 of the closure head member to tension the spring.

The pusher tripping spring 32 is provided with an extension spring portion 53 which bears against the under surface of the closure head member and is adapted to automatically raise the housing and closure head members, when they are released by retraction of the pusher, to expose the staple rail for the loading of a staple strip thereon.

The top wall 43 of the closure member is curved at its rearward end to enclose the rearward end of the rail, being preferably curved on a radius of the pivot pin 19, and in the open position of the housing and closure head member the edge 54 of this curled portion is adapted to abut a transversely bent lug 55 provided upon the rail in the path of rotary movement of the edge 54, thus limiting the open position. In Fig. 6 the housing and closure head members are in partially open position. A spring 56 secured to the base 10 by a rivet 57 normally engages over the upper surface of the lug 55 to prevent upward swinging movement of the rail as the housing and closure members are swung to open position. The arrangement of this spring is such that downward swinging movement of the rail is permitted during the stapling operation. Also by exerting sufficient upward pressure on the rail it will release from the spring 56 to permit the rail, housing and closure head member to be swung to an open position as shown in Fig. 8, where the machine may be used without the anvil as a tacker. In this position the spring 56 engages in a notch 58 in the end of the closure head member to retain the base against looseness.

In the normal use of the machine the staple rail 16 is yieldably retained in a substantially horizontal position by means of a plunger 59 slidably disposed in a hole 60 in the base 10 and having a head 61 engaged with the under-surface of the rail forwardly of the spring 56, a helical spring 62 being disposed between the head 61 and the base 10.

Upon the upper side of the closure head member there is removably secured a facing member 63 which may be formed of sponge rubber or other suitable material and which is moulded to provide an attractive shape conforming substantially to the streamlined design of the machine, the forward end of the facing where it is engaged by the palm of the hand when the machine is being operated being preferably widened out. The attachment means for this facing consists of a series of integral flanged buttons 64 formed upon the under surface which are interlockingly inserted in a series of holes 65 provided in the top wall 43 of the closure head.

Obviously this facing member may be readily

removed when desired for the purpose of removing it.

At the forward ends of the staple rail the side walls have their lower edges projected downwardly, as at 66, so that when the parts are depressed toward the base to grip the material prior to stapling as shown by dot-and-dash lines in Fig. 1, these portions 66 will contact the material while there will be a slight clearance between the material and the housing member. As a consequence the rail is pressed upwardly with respect to the housing member during the stapling operation causing the pusher to have its finger grip portions 26 pressed tightly against the surfaces of the flanges 42 of the housing member, to retain the pusher member against the forward pressure normally exerted thereon by the spring 28, and thus remove forward pressure upon the staple being driven which pressure otherwise creates frictional resistance between the staple and the front wall of the housing member. As this friction is removed during the stapling operation the staple may be driven with less force than would otherwise be required. This also eliminates possibility of clogging of the staples through the dragging action of the staple being driven upon the adjacent staple of the strip.

The operation is as follows:

With the housing member in its normal closed position the staple strip A is pressed forwardly by the pusher member 24, so that the foremost staple is in the staple driving passage between the forward end of the rail and the front wall 34 of the housing member. The housing member is held in parallel operative relation with the rail through the interlocking engagement of the finger grip flange portions 26^a of the pusher with the flanges 42 of the housing member. In order to drive a staple the closure head member is depressed causing the housing member to swing downwardly into engagement with the work as shown in dot-and-dash lines in Fig. 1. The housing member being thus restrained against further downward movement continued pressure on the closure head causes the spring 49 to be depressed, the forward end of this spring, which constitutes the driving means for the staple driving plunger member 38, causing the latter to be moved downwardly in its guide channels 37. The staple disposed in the driving passage is thereupon driven downwardly into the work and clinched by the anvil 11. Upon release of the closure head member after completion of the stapling operation the spring 49 returns the staple driving plunger and the closure member to their normal positions, this position being determined by abutment of the forward end of the spring 49 with the upper end of the slot 52.

During the staple driving operation the downwardly projecting portions 66 of the rail engage the material being stapled, as shown in dot-and-dash lines in Fig. 1 and this, combined with the downward pressure exerted upon the housing, causes the pusher member to be forced upwardly, tightly engaging the finger grip portions 26 with the under-surfaces of the flanges 42, thus restraining the forward pressure of the pusher member under the force of the spring 28. The pressure upon the staple being driven and frictional resistance between the staple and the wall 34 is therefore eliminated, and the staple may be driven with greater ease than would otherwise be the case.

In order to reload the machine with a staple

strip the pusher is manually retracted, the rearward end of its upper surface engaging beneath the spring 32 causing it to be tripped to the inclined position as shown in Fig. 6, the spring 28 drawing the forward clip lugs 25 into locking engagement with the abutment walls 23. As the pusher is retracted the finger grip flange portions 26^a move clear of the flanges 42 thus releasing the housing so that it swings upwardly into open position under the force of the spring 53. The entire top, front and side surfaces of the rail are now entirely exposed, and the staple strip may be placed thereon, without having to guide it or direct it into channels, as has been the case with other types of stapling machines.

With the staple strip in place the housing and closure head members are pressed downwardly to closed position, whereupon the staple strip retaining portion 41 engages the upwardly tilted pusher member and depresses it to the point where the forward clip lugs 25 are disengaged from the abutment walls 23, the spring 28 then drawing the released pusher forwardly, bringing the finger grip flange portions 26^a into interlocking sliding engagement with the flange 42.

When it is desired to use the machine as a tacker, without the anvil, the base 10 is swung to the position shown in Fig. 8, in which position the spring 56 engages the recess 58 to retain the base in this open position, so that it may be conveniently used as a handle in manipulating the machine.

In Figs. 9 to 15 of the drawings I have illustrated a modification of the invention in which the pusher means for the staple strip is adapted to be automatically retained against forward movement upon opening movement being imparted to the housing and closure head members, and in which the housing and closure head members are retained in closed and open position respectively by double acting spring means. The rail 16^a is of inverted U-shape cross-section, and in general is substantially like the rail 16 of the first embodiment, except that the arm is provided at its rearward end with inwardly offset bearing portions 17^a—17^a mounted upon the pivot pin 19. These portions 17^a have a transverse spring mounting portion 61 at their forward ends bent inwardly from one side portion 17^a, and to the under side of which there is secured by rivets 68 the forward end of a flat leaf spring 69, which engages the flat lower horizontal edges of the side portions 17^a and extends rearwardly to a point substantially rearwardly of the pivot pin 19.

The rearward bearing portions 36^a—36^a of the sides 35—35 of the housing member are each provided with a flat surface 70 which in the normal closed position of the housing member is in a horizontal line parallel to the rail 16^a, and which is engaged by the spring 69 which projects laterally beyond the bearing portions 17^a of the rail for this purpose. The engagement of the spring with the flat surfaces 70 rearwardly of the pivotal axis of the pivot pin 19 tends to rotate the housing member in counterclockwise or closing direction, the closing position being determined by outwardly bent lugs 71 provided near the forward ends of the side portions of the staple rail 16^a which engage notches 72 in the lower edges of the side portions 35 of the housing member. The bearing portions 36^a are also provided with flat surfaces 73 extending at an obtuse angle to the flat surfaces 70, and which are adapted to be engaged by the spring in the

open position of the housing and closure head member as shown in Fig. 14. In moving from closed to open position, and vice versa, the peak between the inclined surfaces 70 and 73 depresses the spring 69, the spring snapping into flat retaining engagement with the respective surfaces 70 and 73 in the respective closed and open positions.

During movement from closed to open position the rail is retained against swinging movement by means of a retaining spring 14 mounted upon the base 10 and engaged over the transverse spring mounting portion 67, the action of this spring being substantially like that of the spring 56 in the first embodiment.

The base 10 is encased with a covering 75 of rubber and at a point rearwardly of the spring 14 and forwardly of the pair of pivot pins 19 there is provided a rubber bumper or spring portion 76 integrally moulded with the rubber covering 75, and which engages the under surface of the spring 69 near its forward end to normally support the rail in horizontal position while permitting it to be depressed during the stapling operation. The anvil portion 11 of the base 10 is exposed while the remainder of the base is encased in the rubber cover 75.

The pusher member 77 consists of a rectangular cross-section sheet metal piece extending beneath the rail, upwardly at the sides of the rail, and inwardly at the top of the rail, the inwardly extending top portions being bent upwardly to provide spaced flanges 78 between which there is pivotally mounted upon a pin 79 a locking pawl 80, this pawl having a tooth 81 in its lower edge forwardly of the pivot pin 79 which in the open position of the housing member and closure head is adapted to drop into engagement with ratchet teeth 82 pressed in the upper surface of the staple rail, these ratchet teeth being rearwardly directed so that upon engagement of the pawl therewith the pusher is locked against forward movement under the pulling action of the spring 28. The pawl 80 is so shaped that its major portion is forwardly of the pivot 79 so that the forward end drops by gravity to engage the tooth 81 with the teeth of the rail. The portion of the pawl rearwardly of the pivot 79 constitutes an actuating finger which in the closed position of the housing member is engaged by the staple strip retaining member 41^a to swing the pawl into releasing position, as shown in Fig. 9, with the tooth 81 out of engagement with the ratchet teeth 82 so that the pusher is free to be pulled forwardly by the spring 28.

The member 41^a is provided with an upwardly embossed channel 83 in which the flanges 78 and the pawl 80 are slidably engaged in the closed position of the housing and closure head members. The spring 28 is connected to a lug 84 bent upwardly from the base portion of the pusher member. The lower forward corners of the pusher are notched, as at 85 to engage the stop shoulders 86 provided on the lugs 71, to limit the forward movement of the pusher with its forward edge aligned with the forward edge of the rail. These shoulders 86 also centralize the forward end of the rail with respect to the housing member.

The operation is as follows:

Fig. 9 shows the normal operative position in which the housing and closure members are closed and maintained in such closed position by pressure of the spring 69 against the flat surface 70, the pawl 80 of the pusher being held in re-

leased position by engagement of the staple strip retaining member 41^a therewith, so that the pusher is drawn forwardly by the spring 28. When it is desired to reload the machine with a staple strip the housing and closure head members are raised to the open position, as shown in Fig. 14, the spring 69 snapping into engagement with the flat surfaces 73 to retain them in this open position. As soon as the raising movement of the housing member is initiated the staple strip retaining member 41^a raises with respect to the pawl 80 allowing it to drop by gravity to engage its tooth 81 with the ratchet teeth 82 thereby causing the pusher to be automatically locked in any position where it happens to be when the housing member is raised. This is especially important where staples remain upon the rail, and prevents any possibility of these staples being shot forwardly therefrom. The pusher is thereupon retracted to expose the forward end of the rail, the pawl ratcheting over the teeth 82 during the retracting movement but locking therewith against any forward movement under pull of the spring 28. The staple strip is thereupon placed upon the exposed rail, and the housing and closure head members moved to closed position, in which position the staple strip retaining member 41^a engages the raised rearward end of the pawl and releases it from the ratchet teeth 82.

When it is desired to use the machine as a tacker the rail, housing member and closure head member are swung as a unit relatively to the base member by exerting sufficient pressure upon the rail to overcome the retaining action of the spring 14. In the open position as shown in Fig. 14 dot-and-dash lines in Fig. 9 the curved rearward end of the top wall 43 of the closure head member engages the rubber spring bumper 76 compressing it, so that the base is retained in open position by the swedging action between compressed rubber bumper and the rearward end of the closure head member.

In Figs. 16 and 17 I have illustrated a further modified form of pusher member and rail, which is substantially the same in its action as the pusher member shown in Figs. 9 to 15. This modified pusher member 87 consists of a tubular rectangular piece of sheet metal disposed about the rail 16^b and provided at the forward end of its bottom wall with an upwardly directed tooth 88 opposed to ratchet teeth 89 provided upon the lower edge of the side wall of the rail. The vertical dimension of the pusher is such that sufficient clearance is provided to enable it to have a swinging movement of the rail. A spring 90 is secured to the under side of the upper wall of the pusher near its rearward edge by means of a rivet 91, the forward end of this spring adapted to exert pressure between the forward end of the pusher and the top of the rail to swing the forward end of the pusher upwardly under the forward pull of the spring 28 which is connected to a lug 92 provided upon the lower wall of the pusher.

The staple retaining member 41^b of the housing is adapted in the normal operative position to engage the upper surface of the pusher to compress the spring and retain the pusher in parallel relation to the rail, the tooth 88 being depressed out of engagement with the ratchet teeth 89 so that the pusher is free to be drawn forwardly upon the rail by the spring 28. Upon raising of the housing member to expose the rail, as shown in Fig. 16, the spring 90 tilts the forward

end of the pusher upwardly engaging the tooth 88 with the ratchet teeth 89, thus restraining the forward movement of the pusher. Upon closing of the housing member the staple strip retaining member 41^b engages the upper surface of the pusher and depresses the tooth 88 from engagement with the ratchet teeth 89.

I have illustrated and described preferred and satisfactory embodiments of the invention, but it will be understood that changes may be made therein, within the spirit and scope thereof, as defined in the appended claims.

Having thus described my invention what I claim and desire to secure by Letters Patent is:

1. In a stapling machine, a staple carrying rail adapted to have a staple strip of U-shape staples mounted thereon, a housing member movably mounted with respect to said staple rail for movement between closed and open positions including a front wall rigidly fixed to said housing member, a staple strip pusher slidably on said rail, spring means exerting a forward force on said pusher, pusher locking abutment means carried by said rail, locking means carried by said pusher movable into engagement with said locking abutment means for securing said pusher against forward movement in the open position of said housing member, and means on said housing adapted to move said locking means into inoperative position relatively to said locking abutment means in the closed position of said housing.

2. The invention as defined in claim 1, further characterized by interlocking means cooperating between said pusher and said housing member adapted to retain the housing member in closed position.

3. The invention as defined in claim 1, further characterized by interlocking means cooperating between said pusher and said housing member adapted to retain the housing member in closed position within a predetermined range of movement of said pusher.

4. The invention as defined in claim 1 further characterized by means cooperating between said pusher and housing member adapted to retain the housing member in closed position within a predetermined range of movement of said pusher, said means being inoperative rearwardly of said predetermined range of movement of said pusher.

5. The invention as defined in claim 1, further characterized by means cooperating between said housing member and pusher locking means adapted to render the latter inoperative in the closed position of said housing member whereby said pusher is released and means cooperating between said pusher and housing member adapted to retain the housing member in closed position upon release of said pusher.

6. The invention as defined in claim 1, further characterized by means cooperating between said pusher and housing member adapted to retain the housing member in closed position within a predetermined range of movement of said pusher, said means being inoperative to retain the housing member in a predetermined retracted position of said pusher rearwardly of said range of movement, said pusher locking means being arranged to operate only at a point rearwardly of said predetermined range of movement.

7. The invention as defined in claim 1, fur-

ther characterized by means cooperating between said pusher and housing member adapted to retain the housing member in closed position within a predetermined range of movement of said pusher, said means being inoperative rearwardly of said predetermined range of movement, and spring means arranged to move said housing member to open position upon release by said pusher.

8. In a stapling machine, an anvil base, a staple carrying rail pivotally mounted at one end at said base, a housing member comprising a front wall portion and side wall portions extending rearwardly therefrom and pivotally mounted at its rearward end with respect to said rail, said housing member adapted to be moved between closed and open positions with respect to said rail, said front wall and side walls adapted to laterally enclose the front and sides of the rail in closed position, and to expose said front and sides in open position, a closure head member pivotally mounted at its rearward end coaxially with respect to said housing member, a staple driver carried by said housing member, and a driving connection between said closure head member and said staple driver.

9. In a stapling machine, an anvil base, a staple carrying rail, a transverse pivot mounting for said rail mounted upon one end at said base, a housing member comprising a front wall portion and side wall portions extending rearwardly therefrom and pivotally mounted at their rearward ends upon said pivot mounting, said housing member adapted to be moved between closed and open positions with respect to said rail, and a closure head member including top, front and side wall portions disposed within the upper open side of said housing, said side wall portions being pivotally mounted upon said pivot mounting.

10. In a stapling machine, a rail, a housing member movably mounted in overlying relation with respect to said rail, a staple strip pusher mounted upon said rail normally beneath said housing, spring means normally exerting forward pressure upon said pusher, cooperative locking means respectively on said pusher and rail adapted to secure said pusher with respect to said rail, and means cooperating between said locking means and said housing member adapted to render said locking means inoperative in the closed position of the housing member.

11. In a stapling machine, a staple carrying rail, a housing member including a front wall and side walls extending rearwardly therefrom said front wall being forwardly spaced with respect to the forward end of said rail to provide a staple driving passage, a staple driver mounted upon said front wall for movement in said passage, a closure head member mounted within said housing including a top wall, a front wall and side walls, a spring member carried by said housing member engaging said front wall of said closure member and said staple driver and constituting a driving connection between said closure member and said staple driver.

12. In a stapling machine, a staple carrying rail, a housing member having a staple driving passage, a staple driver slidably mounted in said passage, a closure head member movably mounted with respect to said housing, a spring carried by said housing and engaging said closure member to exert upward pressure thereon, said housing having means engaged by said spring to limit the upward movement of said spring and closure member, said spring being also

engaged with said staple driver whereby said closure member, spring, and staple driver move as a unit.

13. In a stapling machine, a staple carrying rail, a housing member, staple driving means carried by said housing member, a staple pusher on said rail, spring means normally exerting a forward force on said pusher, said pusher including a laterally disposed portion positioned vertically above and in contact with a portion of said rail, a laterally disposed portion positioned vertically beneath and in contact with a portion of said housing, and an interconnecting portion between said laterally disposed portions, whereby relative vertical compressive movement between said housing and said rail draws said pusher vertically downward upon said rail to frictionally retain said pusher against the forward force of said spring means during the stapling operation.

14. In a stapling machine, a staple carrying rail, a housing member, staple driving means carried by said housing member, a staple pusher on said rail, spring means normally exerting a forward force on said pusher, means on said staple rail adapted to engage the material being stapled, there being a clearance between said material and the staple housing whereby there is a relative compressive force exerted between said housing and said rail during the stapling

operation, said pusher including a laterally disposed portion positioned vertically above and in contact with a portion of said rail, a laterally disposed portion positioned vertically beneath and in contact with a portion of said housing, and an interconnecting portion between said laterally disposed portions, whereby relative vertical compressive movement between said housing and said rail draws said pusher vertically downward upon said rail to frictionally retain said pusher against the forward force of said spring means during the stapling operation.

15. In a stapling machine, an anvil base, a staple rail pivotally mounted upon said anvil base, a staple housing pivotally mounted with respect to said rail and adapted to be moved between closed and open positions with respect to said rail, spring means releasably securing said rail with respect to said base whereby said rail is retained in a predetermined position with respect to said base upon movement of said housing member to open position, said spring being also adapted to be released to permit unitary movement of said rail and housing member with respect to said base to a position non-opposed to said base, and means adapted to yieldably retain said rail and housing member in said last mentioned position.

MAX VOGEL.
